WELL PUMPING DEVICE

George W. Miller and William L. Kimsey,
Sapulpa, Okla.

Application May 20, 1940, Serial No. 336,234

4 Claims. (Cl. 74—593)

This invention relates to well pumping devices and more particularly to a device of that character for removably connecting a well pumping rod line with a power transmission mechanism in such a manner as to "hook-off" the rod line and well relative to the power predeterminedly, the principal object of the present invention being to provide a convenient, relatively economical and highly efficient device for the noted purpose. Other objects of the present invention are to provide for adjusting the device to "hook-off" the well at a predetermined fluid level in the well; to provide for efficiently operating a number of wells by a single power at the same time; to prevent damage to wells and pumping equipment therefor; to provide for deviation of movement of the power and rod line without injuring the "hook-off" device; and to provide improved elements and arrangements of them in a well pumping device of this character.

In accomplishing these and other objects of the present invention, I have provided improved details of structure, the preferred form of which is illustrated in the accompanying drawing, wherein:

Fig. 1 is a side elevational view of a well pumping device embodying the features of the present invention.

Fig. 2 is a longitudinal vertical cross section through my improved well pumping device showing the arrangement for unhooking a rod line relative to a power.

Fig. 3 is a transverse vertical cross-section through the device, illustrated in Figs. 1 and 2, substantially on the line 3—3, Fig. 2.

Fig. 4 is a detail side elevational view of a latching device, the same being shown in inoperative position relative to an associated latching device on a rod line.

Fig. 5 is a transverse section taken on the line 5—5, Fig. 2.

Fig. 6 is a fragmentary plan view partly in horizontal section of the hook end of the well rod line.

Referring more in detail to the drawing:

1 generally designates a well pumping device which preferably includes a post 2 that may, for convenience, take the form of a pipe section embedded and suitably anchored in the ground near a power transmission mechanism, not shown. The post is preferably vertically arranged and is provided with aligned slots 3 and 4, the post preferably being braced at opposite sides of the slots by struts 5, substantially as shown.

6 designates a bar that forms a part of a

pumping rod line, said bar is connected at one end by a coupling with a conventional rod line 8 leading to pumping devices in a well, not shown, the other end of the bar being provided with a head 9 having a socket 10 therein for receiving the tongue 11 of a clevis 12. The socket 10 is preferably flared at its outer end to allow lateral swinging movement of the clevis under control of a pivot pin 13 extending through aligned apertures in the head 9 and clevis tongue 11 respectively, the pin being pivotally secured in the head by a nut 14.

The clevis is also provided with a slot 15 to receive a hook 16 or the like that is connected with a suitable power transmission mechanism, not shown.

Mounted on the bar 6 between the post 2 and rod line 8 is a weight 17 or the like, the weight being adjustable longitudinally on the bar, as by the set screw 18, relative to a stop collar 19 fixed to the bar 6 between the post 2 and head 9, the stop collar having a depending foot member 20 the inner face of which, relative to the post, forms a shoulder 21.

22 designates a standard arranged adjacent the post on the rod line side thereof in alignment with the slots therein, the standard having a yoke at its upper end, the spaced arms 23 of which have aligned apertures in which a bearing shaft 24 is arranged to rotatably support a roller 25 that provides a roller bearing support for the bar when it is moved in one direction by the hook 16 upon actuation of the power and in the other direction by the weight of rods to pump the well.

On the power or lift stroke of the bar 6, i. e., to the left relative to Figs. 1 and 2, the rods are under tension and are maintained in the same substantially horizontal plane, as shown in Fig. 4.

On the drop stroke of the bar, i. e., to the right relative to Figs. 1 and 2, the rods are under tension until such time as the usual well pump plunger "hits" fluid in the well, at which time slack is produced in the rod line, and, aided by the weight 17, the bar 6 pivots about the roller 25 to lower the weighted portion thereof and raise the rear portion thereof, the boss and foot member 23 consequently being lifted relative to the weight.

When oil or other liquid in the well being pumped is reduced to a relatively low level, tension is applied to the rod line throughout the length of its stroke, the result of which is that the rod line is maintained in the same sub-

stantially horizontal plane at all times, i. e., on both power and drop strokes.

Upon exhaustion of fluid from the well, severe wear is applied to pumping apparatus and the oil, for example, in the well is damaged.

It is, therefore, desirable to "hook-off" an exhausted well before damage occurs.

Ordinarily, a single power is employed to pump a number of wells over a relatively large area. The well pumper's attention may, and often is, required at locations on a multiple well "lease," for example, some distance away from a particular exhausted well and it is, therefore, further, desirable that the exhausted well be "hooked-off" as and when it becomes exhausted.

In effecting the latter desideratum, the post 2 is preferably provided with a bracket 26 secured as by fastening devices 27 to the post and having a slot 28 aligned with the slots 3 and 4 in the posts to provide for passing the bar 6. The lower end of the bracket consists of a guide 29 extending laterally of the post in parallel relation to the bar. In the angle between the bracket proper and guide, an arcuately shaped block-guide 30 is arranged and a guide slot 31 is longitudinally arranged in the guide 29.

A slide-block 32, of less length than the slot 31, is slidably mounted in the slot 31, the slide-block having arms 33 and 34 on its upper end slidably mounted on the upper face of the guide 29. The slide-block is normally maintained in retracted condition, as shown in Fig. 1, by a spring 35, one end of which bears against the arm 34 and the other end of which is mounted in a recess 36, the outer enlarged portion 37 of which recess also receives the end of the arm 34, when the spring is compressed.

38 and 39 designate pairs of links pivotally mounted at their lower ends on the slide-block 32 and at their upper ends on a "knock-off" or "hook-off" block 40, as by pivot pins 41, the upper face of which block 40 is grooved, as at 42, to form a bearing seat for the bar 6.

A latching device 43 is mounted in a recess 44 of the slide-block 32 as by pivoting an arm 45 thereof on a pivot pin 46 arranged transversely of the recess in the slide-block, the latching device normally tending to rock forwardly, or to the right, Fig. 2, and downwardly, and being controlled in its downward movement by a nose 47 thereon which bears on the slide-block. A shoe 48 is mounted on the latching device, as by a fastening device 49, and projects upwardly therefrom substantially into the path of the foot member 20 on the stop collar 19 and bar 6.

The operation of a well pumping device constructed as described is as follows:

Assuming the well to have accumulated liquid therein and the bar 6 to be hooked on to the power by the hook 16, the power is energized and imparts a power stroke (to the left, Figs. 1 and 2) to the rod line 8 to maintain the same in taut, tense and plane condition. The foot-member 20 on the bar 6 strikes the shoe 48 on the slide-block latching device, but passes over the same due to pivotal movement of the latch.

On the down stroke (to the right, Figs. 1 and 2) the well pump plunger "strikes" liquid in the well, normally before the drop stroke is completed, and produces slack in the rod line which, aided by the weight 17 on the bar, "kicks" the foot-member 20 over latch shoe 48 on the drop stroke.

As the well is exhausted of liquid, the drop stroke approaches completion before the "kick"

is applied to the foot-member and, depending somewhat upon the position of the weight 17, the foot-member contacts the latch shoe and moves the slide-block forwardly against tension of the spring 35.

As the slide-block moves forwardly, the "knock-off" block rides up the arcuate face of the guide 30 into supporting relation to the bar and in line with the collar 19 on the bar, thus halting movement of the rod line in the direction of the well. The power continues, however, and continued movement of the hook 16 in the direction of the well causes the hook to drop, by gravity, through the slot in the clevis, to "hook-off" that well, yet allowing continued pumping of other wells.

When it is desired to again "hook-on" the well, the power is again actuated and when the hook 16 is positioned below the clevis slot it may be moved upwardly into engagement with the clevis to again "hook-on" the well.

It is apparent, therefore, that a convenient, relatively economical and highly efficient well pumping mechanism is provided by the present invention.

What we claim and desire to secure by Letters Patent is:

1. In a device of the character described, a rod line for transmitting reciprocable motion from a power mechanism to a well pumping mechanism which applies tension thereto, said power and well pumping mechanism effecting intermittent motion of the rod line in their respective directions, supporting means spaced from one

end of the rod line whereby weight of the rod line causes deflection thereof varying with the tension applied thereto, stop means, an abutment adjacent the rod line, means actuated by the rod line upon predetermined variation between the deflections thereof occurring during the respective motions toward the well pumping mechanism for moving the stop means into engagement with the rod line, and abutments for stopping motion of the rod line and effecting disengagement of the rod line from one of the mechanisms.

2. In a device of the character described, a reciprocable rod line, means supporting the rod line whereby weight of the rod line causes deflection thereof, power means connected to one end of the rod line, load means connected to the other end of said rod line which applies tension thereto variable with said load, said power and load means effecting intermittent motion of the

rod line in their respective directions, a block, means slidably supporting the block, and means actuated by the rod line upon a predetermined variation between the deflections thereof occurring during the respective motions of the rod line toward the load means for moving the block into position to stop movement of the rod line in one direction and effecting disengagement of the rod line from the power means.

3. In a device of the character described, a reciprocable rod line, means supporting the rod line whereby weight of the rod line causes deflection thereof, means connected to the respective ends of the rod line for reciprocating said rod line and intermittently applying pulling force to the respective ends thereof, said deflection of the rod line varying with the pulling force acting on the rod line, means on the rod line for increasing deflection thereof, and means actuated by the rod line upon predetermined variations between the deflections thereof occurring

during the respective motions thereof toward one of the pulling means for effecting disengagement of the rod line from one of the means applying force thereto.

4. In a device of the character described, a rod line, means supporting the rod line whereby weight of the rod line causes deflection thereof, means connected to the respective ends of the rod line for reciprocating said rod line and intermittently applying pulling force to the respective ends thereto, said deflection of the rod

line varying with the pulling force acting on the rod line, a block, means slidably supporting the block, an abutment in the path of the block, and means on the block engageable with the rod line when the deflection of the rod line varies a predetermined amount whereby the block is moved into engagement with the abutment and rod line for stopping movement of the rod line in one direction.
